CLAIM

The ornamental design for a handheld terminal device, as shown and described.

DESCRIPTION

FIG. 1 is a bottom, front and right side perspective view of handheld terminal device showing our new design;

FIG. 2 is a top, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

(Continued)

The broken lines in the drawings illustrate portions of the handheld terminal device and form no part of the claimed design.

1 Claim, 6 Drawing Sheets
